of Delaware

Application July 30, 1942, Serial No. 452,820

14 Claims. (Cl. 250—36)

1

This invention relates generally to thermionic tube circuits and particularly to a circuit utilizing a thermionic tube which includes a plurality of control electrode elements.

In thermionic vacuum tubes of the type including two control electrodes, a screen electrode and a suppressor electrode in addition to the usual cathode and anode electrodes, the first control electrode may be connected to control directly the cathode current. The second control electrode may be arranged to control a virtual cathode formed by the cathode emission, by maintaining the second control electrode at a slightly positive potential with respect to ground, a condition which may be established by connecting the cathode to ground through a cathode resistor. With such an arrangement, as the first grid is driven positive, the cathode will follow it, and the second grid will become negative with respect to the cathode to reduce or cut off the anode current. Under these conditions the anode voltage changes in phase with the potentials applied to the first control electrode. Various circuit arrangements, to be described hereinafter, may be employed to utilize the above described characteristics of such a thermionic tube for generating oscillations. By proper selection of feedback elements connecting the anode to the first control electrode, or the screen to the second control electrode, or both, oscillations of complex wave form may be generated under extremely stable operating conditions. The basic circuit may also be utilized to provide an amplifier in which the input and output potentials are substantially in phase. It should be understood that amplifiers according to the invention may be connected in cascade arrangement in the same manner as conventional amplifiers.

Among the objects of the invention are to provide a new and improved method of and means for generating oscillations by means of including a thermionic tube having a plurality of control electrodes. Another object of the invention is to provide a new and improved method of and means for generating oscillations of complex wave form. Another object of the invention is to provide a new and improved method of and means for generating oscillations which utilizes a thermionic tube having a plurality of control electrode elements, in which the anode may be reactively coupled to the first control electrode, and the screen electrode may be reactively coupled to the second control electrode. Another object is to provide an improved method of and means for generating oscillations which utilizes a multi-

2

element thermionic tube in which feedback is provided by a reactive circuit connected between the screen electrode and the second control electrode. Still another object of the invention is to provide a new and improved method of and means for generating oscillations which utilizes a multi-element thermionic tube in which the second control electrode is maintained at a potential positive with respect to the bias potential applied to the first control electrode.

Among other objects of the invention are to provide a new and improved method of and means for amplifying signals wherein the output voltages are maintained in substantially the same phase as the input signals. Another object is to provide a new and improved method of and means for utilizing a single thermionic tube, having a plurality of control electrode elements, as an amplifier in which input potentials applied to one control electrode are amplified to derive in-phase potentials in the anode circuit. Another object is to provide an improved method of and means for utilizing a multi-electrode thermionic tube in which potentials applied to one control electrode are amplified to derive in-phase voltages of increased amplitude in the screen electrode circuit.

The invention will be described by reference to the accompanying drawing of which Fig. 1 is 30 a schematic circuit diagram of one embodiment of said oscillator; Fig. 2 is a schematic circuit diagram of a second embodiment of said oscillator; Fig. 3 is a schematic circuit diagram of a third embodiment of said oscillator; Fig. 4 is a 35 schematic circuit diagram of one embodiment of said amplifier; and Fig. 5 is a schematic circuit diagram of a second embodiment of said amplifier. Similar reference numerals are applied to similar elements throughout the drawing.

Referring to Fig. 1, a multi-element thermionic vacuum tube 1, such as the RCA type 6L7 is provided with heater and anode potentials, not shown. The cathode is connected to ground, and to the negative terminal of the anode power supply, 45 through a cathode resistor 2. The suppressor electrode R is connected to the cathode. The positive terminal of the anode power supply is applied directly to the screen electrode S and through an anode resistor 3 to the anode. The first control electrode T is connected through a grid resistor 4 to ground. The second control electrode U is connected to the positive terminal of a source of bias potential 5, which may be a battery. The negative terminal of the source of 50 bias potential 5 is connected to ground. A feed- 55 bias potential 5 is connected to ground. A feed-

back circuit, which may be either inductive or capacitive, includes a capacitor 6 which is connected between the anode and the first control electrode. A load circuit may be connected to the anode, through a coupling capacitor 8, and to ground. Any other well known method of coupling a load circuit may be employed.

Referring to Fig. 2 a multi-element thermionic tube, of the same type as described in Fig. 1, is provided with suitable sources of heater and anode potentials, not shown. The positive terminal of the anode power source is connected directly to the anode, and through a screen coupling resistor 13, to the screen electrode S. The negative terminal of the anode power supply is connected to ground. The suppressor electrode R is connected to the cathode. The cathode is connected to ground through a cathode resistor 2. The first control electrode T is connected to ground. The second control electrode U is also connected to ground through a grid resistor 14. The screen electrode is connected to the second control electrode through a feedback circuit, which includes a capacitor 16. The feedback circuit may have either inductive or capacitive characteristics. Output may be provided to a load through a blocking capacitor 8 connected to the tube anode in the same manner as described and shown in the circuit of Fig. 1.

In Fig. 3 a multi-element thermionic tube 1, of the same type as described heretofore, includes sources of heater and anode potential, not shown. The positive terminal of the anode power source is connected to the anode through an anode resistor 3, and to the screen electrode S through the screen resistor 13. The negative terminal of the anode power supply is connected to ground. The suppressor electrode R is connected to the cathode. The cathode is connected to ground through the cathode resistor 2. The first control electrode T is connected to ground through the grid resistor 4. The second control electrode U is connected through the resistor 14 to the positive terminal of a source of bias potential 5, which may be a battery. The negative terminal of the source of bias potential is grounded. Two feedback circuits are provided, which may be of similar or different characteristics. The first feedback circuit which includes a switch 11, a capacitor 6, and an inductor 6' is connected between the anode and the first control electrode. By operation of the switch 11, the feedback circuit may be of either inductive or capacitive characteristics. The second feedback circuit, which includes a switch 12, a capacitor 16, and an inductor 16' is connected between the screen electrode and the second control electrode. By operation of the switch 12, this feedback circuit may also be of either inductive or capacitive characteristics. Blocking capacitors 8 and 8' respectively permit separate loads to be D.-C. isolated from the anode and screen as in the circuits of Figs. 1 and 2. The blocking capacitors also prevent short-circuiting of the anode and screen voltages through the inductors 6' and 16' when the switches 11 and 12 are actuated.

As explained heretofore, when the second control electrode is maintained at a potential slightly positive with respect to ground, and the cathode is connected to ground and to the negative terminal of the B-power supply through a cathode resistor, the cathode potential will follow the first control electrode potential when that electrode is driven positive. The second control electrode will control the anode current from the

virtual cathode, and will reduce or cut off the anode current in phase with the potentials on the first control electrode. With any of the feedback circuits described, the system will oscillate when sufficient reaction is provided. The apparent gain of the system may also be controlled by the feedback circuit connected between the screen electrode and the second control electrode. As the second control electrode is driven to a negative potential, the screen current will increase (due to the current cut off from the anode), and therefore, the screen voltage will fluctuate in phase with the voltage on the second control electrode, whereby the feedback circuit will provide continuous oscillations. As shown in Fig. 3, a combination of anode-to-first control electrode, and screen-to-second control electrode feedback circuits may be utilized to provide oscillations of desired wave form and amplitude. Signals of different wave form may be derived simultaneously from the anode and screen electrode circuits. Signal characteristics may be determined by the feedback circuit and tube electrode circuit constants.

In Fig. 4 a multi-element thermionic vacuum tube 1, such as the RCA type 6L7, is provided with heater and anode potentials, not shown. The cathode is connected to ground, and to the negative terminal of the anode power supply, through a cathode resistor 2. The suppressor electrode R is connected to the cathode. The positive terminal of the anode power supply is applied directly to the screen electrode S, and through an anode resistor 3 to the anode. The first control electrode T is connected through a grid resistor 4 to ground. The second control electrode U is connected through the switch arm 7 and the switch contact A directly to ground. Input signals are applied between the first control electrode and ground. Amplified output signals are derived in any suitable manner from between the anode and ground. When the switch arm 7 is connected to the switch contact B, the second control grid is connected to ground through a relatively high resistance 10, and is also connected to the anode through a suitable impedance such as a capacitor 9 to provide desired degeneration.

In Fig. 5, a multi-element thermionic tube 1, of the same type as described in Fig. 1, is provided with suitable sources of heater and anode potentials, not shown. The positive terminal of the anode power source is connected through the switch 17 directly to the anode, and through a screen coupling resistor 13 to the screen electrode S. The negative terminal of the anode power supply is connected to ground. The suppressor electrode R is connected to the cathode. The cathode is connected to ground through a cathode resistor 2. The first control electrode T is connected to ground. The second control electrode U is connected to ground through a shunt resistor 7. Input signals are applied to the tube between the second control electrode and ground. The output signals may be derived between the screen electrode and ground. It will be seen that the amplifier circuits described are somewhat similar to the oscillator circuits described heretofore with the exception that the feedback circuits have been omitted. Push-pull output may also be derived from the circuit by connecting an anode coupling resistor in parallel with the switch 17. With the switch open, push-pull output signals are obtainable by connections between the anode and the screen electrode.

When the second control electrode is main-

tained at a potential slightly positive with respect to ground, and the cathode is connected to ground through a cathode resistor, the cathode potential will follow the first control electrode potential when that electrode is driven positive. The second control electrode will control the anode current from the virtual cathode, and will reduce or cut off the anode current in phase with the potentials on the first control electrode. As the second control electrode is driven to a negative potential, the screen current will increase (due to the current cut-off from the anode), and therefore the screen voltage will fluctuate in phase with the voltage on the second control electrode.

Thus the invention comprises a new and improved method of and means for utilizing a multi-element thermionic tube for generating oscillations of complex wave form. The oscillator described utilizes the in-phase characteristics of the anode and first control electrode, and the similarly in-phase characteristics of the screen electrode and second control electrode.

The invention also comprises a new and improved method of and means for utilizing a multi-element thermionic tube for amplifying signals to derive output currents which are in phase with the input currents applied to the device. The amplifier described utilizes the in-phase characteristics of the first control electrode and the anode circuits, or the similarly in-phase characteristics of the second control electrode and screen electrode circuits.

I claim as my invention:

1. A thermionic tube circuit including a tube having at least a cathode, an anode, a screen electrode and a plurality of control electrodes, means including a series cathode resistor connecting said cathode as a follower of one of said control electrodes, means connected to said tube for providing voltages on said screen electrode which are substantially in phase with voltages on one of said control electrodes, means connected to said tube for providing voltages on said anode which are substantially in phase with voltages on another of said control electrodes, at least one feedback circuit connected to one of said control electrodes, and means for applying at least one of said voltages to said feedback circuit to control reaction within said tube circuit.

2. An oscillator including a thermionic tube having a cathode, an anode, a screen electrode, and a plurality of control electrodes, a source of anode potential positive with respect to said cathode, means connecting said positive anode potential to said anode and said screen, a source of bias potential positive with respect to said cathode, a cathode resistor, means including said resistor connecting said cathode to a point of reference potential, means connecting the first of said control electrodes to said point of reference potential, means for applying said positive bias potential to a second one of said control electrodes, reactive feedback means, and means connecting said feedback means between at least one of said control electrodes and at least one of said electrodes connected to said positive anode potential means.

3. An oscillator including a thermionic tube having a cathode, an anode, a screen electrode, and a plurality of control electrodes, a source of anode potential positive with respect to said cathode, means for applying said positive anode potential to said anode and said screen, a source of bias potential positive with respect to said cathode, a cathode resistor, means including said resistor

connecting said cathode to a point of reference potential, means connecting the first of said control electrodes to said point of reference potential, means for applying said positive bias potential to a second one of said control electrodes, capacitive feedback means, and means connecting said feedback means between at least one of said control electrodes and at least one of said electrodes connected to said positive anode potential means.

10 4. An oscillator including a thermionic tube having a cathode, an anode, a screen electrode, and a plurality of control electrodes, a source of anode potential positive with respect to said cathode, means for applying said positive anode potential to said anode and said screen, a source of bias potential positive with respect to said cathode, a cathode resistor, means including said resistor connecting said cathode to a point of reference potential, means connecting the first of said control electrodes to said point of reference potential, means for applying said positive bias potential to a second one of said control electrodes, inductive feedback means, and means connecting said feedback means between at least one of said control electrodes and at least one of said electrodes connected to said positive anode potential means.

trial means.

5. An oscillator including a thermionic tube having a cathode, an anode, a screen electrode, and a plurality of control electrodes, a source of anode potential positive with respect to said cathode, means for applying said positive anode potential to said anode and said screen, a source of bias potential positive with respect to said cathode, a cathode resistor, means including said resistor connecting said cathode to a point of reference potential, means connecting the first of said control electrodes to said point of reference potential, means for applying said positive bias potential to a second one of said control electrodes, reactive feedback means, and means connecting said feedback means between said first control electrode and said anode.

45 6. An oscillator including a thermionic tube having a cathode, an anode, a screen electrode, and a plurality of control electrodes, a source of anode potential positive with respect to said cathode, means for applying said positive anode potential to said anode and said screen, a source 50 of bias potential positive with respect to said cathode, a cathode resistor, means including said resistor connecting said cathode to a point of reference potential, means connecting the first of said control electrodes to said point of reference potential, means for applying said positive bias potential to a second one of said control electrodes, reactive feedback means, and means connecting said feedback means between said second control electrode and said screen electrode.

60 7. An oscillator including a thermionic tube
having a cathode, an anode, a screen electrode,
and a plurality of control electrodes, a source of
anode potential positive with respect to said
cathode, means for applying said positive anode
65 potential to said anode and said screen, a source
of bias potential positive with respect to said
cathode, a cathode resistor, means including said
resistor connecting said cathode to a point of
reference potential, means connecting the first
70 of said control electrodes to said point of refer-
ence potential, means for applying said positive
bias potential to a second one of said control
electrodes, first reactive feedback means, means
connecting said feedback means between said first
75 control electrode and said anode, second reactive

feedback means, and means connecting said second feedback means between said second control electrode and said screen electrode.

8. A device of the type described in claim 5 including a load circuit, and means for connecting said load circuit to said device.

9. A device of the type described in claim 6 including a load circuit, and means for connecting said load circuit to said device.

10. A device of the type described in claim 7 including a load circuit, and means for connecting said load circuit to said device.

11. An amplifier for deriving amplified output signals of substantially the same phase as signals applied to the input of said amplifier including a thermionic tube having a cathode, an anode electrode, a screen electrode and a plurality of control electrodes, means including a series cathode resistor for biasing one of said control electrodes to a potential which is negative with respect to said cathode, a source of anode voltage positive with respect to said cathode, means for applying said positive anode voltage to said anode electrode and said screen electrode, means for applying said input signals between another of said control electrodes and said cathode, means coupling said anode to said one of said control electrodes for providing degeneration, and means for deriving amplified signals of substantially the same phase as said input signals from one of said electrodes connected to said positive voltage source.

12. An amplifier for deriving amplified output signals of substantially the same phase as signals applied to the input of said amplifier including a thermionic tube having a cathode, an anode, a screen electrode and a plurality of control electrodes, means including a series cathode resistor for biasing the second of said control electrodes to a potential which is negative with respect to said cathode, means for applying said input signals to the first of said control electrodes, degenerative feedback means, means connecting said feedback means between said anode and said second control electrode, and means for deriving signals of substantially the same phase as said input signals from between said anode and said cathode.

13. In a signal amplifier including a thermionic tube having a cathode, an anode, a screen elec-

trode and a plurality of control electrodes, the method comprising actuating said cathode as a follower of one of said control electrodes, applying signals to another of said control electrodes, providing degeneration between said anode and one of said control electrodes, and deriving from said amplifier amplified signals of substantially the same phase as said applied signals.

14. In a signal amplifier including a thermionic tube having a cathode, an anode, a screen electrode and a plurality of control electrodes, the method comprising actuating said cathode as a follower of one of said control electrodes, applying signals to another of said control electrodes, providing degeneration between said anode and one of said control electrodes, and deriving from said anode and said cathode amplified signals of substantially the same phase as said applied signals.
